UNITED STATES PATENT OFFICE.

CARL G. KOPPITZ, OF WILKINSBURG, PENNSYLVANIA.

MEANS FOR TRANSFERRING HIGH-POTENTIAL ELECTRIC CURRENTS AS ARCS.

1,233,584.

Specification of Letters Patent. Patented July 17, 1917.

Application filed September 19, 1912. Serial No. 790,771.

To all whom it may concern:

Be it known that I, CARL G. KOPPITZ, a citizen of the United States, residing at Wilkinsburg, in the county of Allegheny 5 and State of Pennsylvania, have invented certain new and useful Improvements in Means for Transferring High-Potential Electric Currents as Arcs, of which the following is a specification.

10 In my applications Serial Numbers 646,988, filed August 31, 1911, and 724,963, filed October 10, 1912, I have described a process of and apparatus for interconverting direct and alternating currents, having a potential of from one or two thousand up to several hundred thousand volts, by synchronously transferring unidirectional currents as arcs between rotating distributors connected to the source of direct current and 15 fixed commutator-segments connected by spaced leads to different portions of a closed alternating-current winding, the distributors being driven in synchronism with the alternating-current phases.

20 The present invention relates to means for increasing the conductivity of the air at the arcing-points, by creating partial vacua thereat.

Referring to the accompanying drawing,—

25 Figure 1 is a diagrammatic view of a portion of an electric converter, illustrating, in section, a rotating terminal of spaced laminae and means for withdrawing the air therethrough;

30 Fig. 2 is identical with Fig. 1, except that a two-part rotating terminal is employed;

Fig. 3 is a sectional side elevation of a modification employing a solid rotating terminal with a peripheral air-passage;

35 Fig. 4 is an end elevation of the same;

Fig. 5 is a sectional side elevation of another modification employing a two-part rotating terminal of solid blocks separated by insulation and surrounded by an air-passage,

40 on the line V—V of Fig. 7;

Fig. 6 is a front elevation of the same; and

Fig. 7 is a horizontal section of the same on the line VII—VII of Fig. 5.

45 The converter illustrated in Fig. 1 comprises an alternating-current winding 1, from which spaced leads 2 extend inward to a circular series of fixed terminals 3. One of the rotating terminals 4, in arcing proximity to the fixed terminals 3, is carried by a radial arm 5, and is electrically connected

by a lead 6 to a central slip-ring 7 on which bears a brush 8, indicated as of positive polarity. This construction is generically that of my specified prior applications. According to the present invention, the rotating terminal 4 is constructed of a series of flat metal laminae, spaced apart to provide intermediate air-passages. The arm 5 consists of a tube, the outer end of which is expanded to receive these laminae, insulated therefrom, and the inner end of which is connected by an air-tight joint to a fixed pipe 9 leading to a vacuum-pump 50. In operation, sufficient air is pumped through the passages between the laminae and pipes 5 and 9 to materially reduce the atmospheric pressure and increase the conductivity of the air-gap at the arcing-point.

The apparatus of Fig. 2 is similar to that of Fig. 1, except that the rotating terminal consists of two sets of spaced laminae, 4^a, 4^b, separated by insulation 10 and separately connected by leads 6, 6' to separate slip-rings 7, 7', on which bear positive brushes 8, 8'. This construction is employed where it is desired to interpose an interrupter in the circuit 6'; as described in my application Serial No. 791,312, filed September 23, 1913.

45 Figs. 3 and 4 illustrate a rotating terminal consisting of a solid rectangular block 4', somewhat smaller than and leaving a peripheral space between it and the expanded end of the tube 5', in which it is carried.

50 Figs. 5, 6, 7 illustrate a modified construction employing a two-part rotating terminal consisting of solid blocks 4^a and 4^b, separated by a sheet of insulation 10'. These blocks, each of which preferably has a removable wearing-face, are carried by and are in electrical contact with the end of a two-part metal elbow 11, fixed on a ring of insulation 12 on the end of hollow radial arm 5^a. The terminal blocks are surrounded by an insulating sleeve 13, leaving an intermediate passage 14 which communicates through holes 15 with the interior of the elbow.

55 Molybdenum, and tungsten, a metal of the molybdenum group, are suitable metals for the arcing terminals, laminae or blocks, on account of their high melting-points and resistance to oxidation.

I claim:

1. Means for transferring high-potential electric currents as arcs, comprising a set of fixed terminals, a movable terminal in arc-

ing proximity thereto, and means for continuously withdrawing air from the vicinity of said movable terminal.

2. Means for transferring high-potential electric currents as arcs, comprising a set of fixed terminals, a movable terminal in arcing proximity thereto, a hollow arm carrying said movable terminal, and a vacuum pump connected to said hollow arm.
- 5 10 3. Means for transferring high-potential electric currents as arcs, comprising a set of

fixed terminals, a movable terminal in arcing proximity thereto, consisting of spaced parallel members, and means for withdrawing air from the arcing zone through the 15 spaces adjacent to said members.

In testimony whereof I affix my signature in presence of two witnesses.

CARL G. KOPPITZ.
